UNITED STATES PATENT OFFICE.

SAMUEL T. SUDDICK, OF BONNE TERRE, MISSOURI.

CUT-OFF FOR RAIN-WATER SPOUTS.

SPECIFICATION forming part of Letters Patent No. 427,206, dated May 6, 1890.

Application filed May 26, 1887. Serial No. 239,474. (No model.)

To all whom it may concern:

Be it known that I, SAMUEL T. SUDDICK, a citizen of the United States, residing at Bonne Terre, in the county of St. Francois and State 5 of Missouri, have invented certain new and useful Improvements in Cut-Offs for Rain-Water Spouts; and I do hereby declare the following to be a full, clear, and exact description of the invention, such as will enable others skilled in the art to which it appertains to 10 make and use the same, reference being had to the accompanying drawings, which form part of this specification.

My invention relates to an improvement in 15 cut-offs for rain-water spouts; and it consists in the construction and arrangement of parts more fully hereinafter described, and pointed out in the claims.

The object of my invention is to provide an 20 automatic cut-off for a rain-water spout, which will be simple in construction, readily applied and detached therefrom, and which will be cheaply manufactured. I attain this object by the device illustrated in the accompanying drawings, in which the same letters of reference indicate like parts in the several views, and in which—

Figure 1 is a perspective view showing the 25 cut-off in an operative position. Fig. 2 is a similar view showing the cut-off in an inoperative position. Fig. 3 is a side view of the cut-off. Fig. 4 is a detail view of the regulating slide and aperture.

In the drawings, A represents the boxing 30 of a rain-water pipe constructed in a rectangular form, with an opening in its front or forward position and having inclined notches a cut in its sides.

B represents an angular-shaped cut-off 35 formed with an oblique upwardly-extending back portion C, a horizontal bottom portion C', and sides C² and C³, which latter are preferably constructed of considerable width to prevent the water from flowing over the same. 40 The dimensions of this cut-off are such as to admit of its insertion in the rectangular box A, and at the same time allowing of a free oscillating movement thereof. Angle-arms or journals D are secured to the sides of the cut-off at a point near its angle. These arms project outward and are bent at right angles on the plane of the horizontal portion, and at

right angles to the upper portion of the cut-off, and have metallic boxes d secured to their outer ends, which are provided with 55 openings, through which they are filled with shot or other heavy suitable material to give them weight. When the cut-off is placed in position in the box A, the arms D rest in inclined notches a, which serve as bearings for 60 the same. On the under side of the end portion of the lower part C' there is a receptacle or tank E, having an opening or tube e in its bottom, which is provided with a suitable stopper or valve consisting of a plug e', having 65 a notch cut lengthwise in it, so that the water will gradually leak out after the rain ceases and allow the weights to bring the cut-off back to its original position. There is a groove F in the center of the cut-off, which 70 extends from near its upper end to a point adjacent to its lower end. At the upper end of the groove F a U-shaped insertion is made, the metal being bent back to form an inwardly-extending lip f, which projects up- 75 ward from the end of the groove, for the purposes hereinafter stated. At the lower end of the groove F is formed an aperture f', which communicates with the tank E, and into which the groove leads. This aperture is 80 preferably of a much larger diameter than the width of the groove, and is adapted to be regulated in size by a slide or valve G, which is pivoted to the under side of the cut-off and may have an arm connected thereto, extending 85 back through an aperture in the tank for manipulating the same.

The operation of my device is as follows: When the cut-off is properly placed in the box A, with the arms D resting in notches a, and 90 the boxes d have been filled with the necessary material to produce sufficient weight to overcome the weight of the lower portion C, the cut-off will be held in a position with its upper end against the back of the box, and 95 the water first entering the spout, accompanied by the dirt which has accumulated on the roof, is carried off by the cut-off and prevented from going into the cistern or tank used for the storage of the water. As the water is thus carried off, the groove F will conduct a sufficient amount of it into the tank E, which will become filled by the time the polluted water has all run off, and thereby con-

stitute a counterweight to the weights *d*, which will be overcome, and the cut-off tilted forward, thus opening the spout and permitting the water to enter the cistern. When the 5 cut-off is in this position, the water in the tank *E* escapes through the tube *e* by leakage through the notch in plug *e'*, and without other provision would permit the cut-off to drop back into its original position during a 10 shower. To overcome this defect in the operation of the device, I provide the lip *f*, which projects into the spout, while the edge of the cut-off is even with its sides. Thus the water striking the inwardly-projecting lip is conducted to the groove, and thence into the tank *E*, and the required weight maintained during the rain. After the rain ceases the water 15 leaks out and the cut-off drops back.

By the construction of the weights as described, and by the valve *G*, I am enabled to govern the amount of water flowing over the cut-off at will, so that if it is desired to have a large amount, as would be the case with large buildings and dirty roofs, it is only necessary to reduce the size of the aperture by 20 the valve *G*.

By the use of the groove *F* the water is conducted into the tank *E* in such a way as to avoid the entering of a great amount of dirt 25 into said tank, as would be the case if the opening extended entirely across the cut-off.

The water is gradually introduced into the tank and the first rush of water and dirt allowed to pass by the aperture, permitting a 30 sufficient quantity of water, substantially pure, to fill the tank, thus rendering it more easily relieved of its weight. When the rain ceases, the cut-off again drops back to an operative position by the leakage of the water 35

through the notch in the plug in the bottom 40 of the tank *E*, as above mentioned.

Having thus fully described my invention, what I claim as new, and desire to secure by Letters Patent of the United States, is—

1. In a rain-water spout, the combination, 45 with a rectangular box having inclined notches and an open side, of a cut-off having weighted arms projecting therefrom and resting in said notches, and a groove formed in its upper side, which extends from a point near its lower end, 50 an inwardly-extending lip in an opening formed at the upper end of the groove, an aperture at its lower end, a tank secured to the under side of the cut-off beneath said aperture, and a notched plug situated in the bottom side of the tank, as set forth.

2. In a rain-water spout, the combination, 55 with a rectangular box having notches therein and an open side, of an angular cut-off having sides with arms projecting out therefrom provided with weighted boxes having openings for filling the same, a groove formed in the center of its upper side, which extends from a point near its upper end to a point near its lower end, an inwardly and up- 60 wardly extending lip in an opening at the upper end of the groove, an aperture at the lower end of said groove, a tank secured to the under side of the cut-off, a slide or valve for regulating the size of said aperture, and a notched plug in the bottom side of said tank, as set forth.

In testimony whereof I affix my signature in presence of two witnesses.

SAMUEL T. SUDDICK.
